J. CAMERON

CUTTING APPARATUS FOR MINING MACHINES

Filed Nov. 6, 1925

Patented May 31, 1927.

1,630,255

UNITED STATES PATENT OFFICE.

JAMES CAMERON, OF HENRYETTA, OKLAHOMA.

CUTTING APPARATUS FOR MINING MACHINES.

Application filed November 6, 1925. Serial No. 67,373.

This invention relates to cutting apparatus especially adapted to be used in conjunction with coal mining machines and it consists in the novel features hereinafter described and claimed.

An object of the invention is to provide an improved cutting apparatus which may be used in conjunction with any practical form of mining machine and which includes 10 a chain made up of blocks and strap plates pivotally connected together and in providing a guide support for the strap and block members so that cutting picks which are carried by the blocks will be firmly supported and held against the coal while the chain is moving around the guiding support.

A further object of the invention is to provide a structure which is simple and durable and capable of operating in hard 20 material without danger of being distorted, disarranged or wedged in the material in which it is operating.

A further object of the invention is to provide blocks of especial design and arrangement of their elements and features whereby the cutting picks are held properly balanced and properly disposed with relation to the median dimensions of the blocks thus causing the picks to cut smooth surfaces in the material along the walls of the kerf which is formed in the material.

In the accompanying drawings:—

Figure 1 is a fragmentary plan view of the cutting apparatus with parts thereof broken away.

Figure 2 is an enlarged fragmentary sectional view thereof cut on the line 2—2 of Figure 1.

Figure 3 is a similar view cut on the line 40 3—3 of Figure 1.

Figure 4 is a plan view of one of the blocks used in the apparatus.

Figure 5 is a side elevational view thereof.

Figure 6 is an edge view of a pair of strap plates used in the cutting apparatus.

Figure 7 is a side elevational view of the strap plates.

Figure 8 is an end view of the strap plates.

The cutting apparatus includes an elongated arm 1 having guide rails 2 extending along its longitudinal edges. The said guide rails are T-shaped in transverse sections. The arm 1 is provided at its edges with longitudinally disposed grooves 1' which receive the intermediate portions of the T-shaped guide rails 2 and the said guide rails

are fixed to the arm by means of rivets 1" which pass transversely through the arm and the intermediate portions of the guide rails 2 as most clearly indicated by the 60 dotted lines in Figures 2 and 3 of the drawings. The heads of the rails are spaced from the edges of the arm. Plates are applied to the opposite sides of the end portions of the arm 1 and a sprocket wheel 4 65 is journaled between the plates and is disposed beyond the end of the arm. The transverse thickness of the peripheral portion of the wheel 4 is substantially equal to the transverse breadth of the heads of the 70 guide rails 2. The wheel 4 is provided at its center and at its opposite sides with bosses 5 which increase the thickness of the intermediate portion of the wheel and the wheel at its intermediate portion is approximately 75 of the same transverse thickness as the thickness of the arm 1.

The cutting apparatus also includes a chain structure adapted to move around the longitudinal edges of the arm 1 and along 80 the guide rails 2 and around the sprocket wheel 4. The chain structure consists of strap plates 6 provided at their edges and at their inner sides with inwardly extending flanges 7 adapted to move along the edges of the arm and in the spaces between the heads of the rails and the edges of the arm as best indicated in Figure 3 of the drawing. The said strap plates are rounded 90 at their outer corners as at 8. The strap plates are arranged in pairs and the members of the pairs are disposed one at each side of the guide rail. The members of each pair are connected together by cross rivets 9 and spacing sleeves 10 are mounted upon the intermediate portions of the rivets and between the inner surfaces of the opposite strap plates as best indicated in Figure 8. The corners of the flanges 7 are beveled as 95 at 11 in order that the said flanges may be readily guided in the spaces between the heads of the rails and the edges of the arm.

The chain structure also includes blocks 12 having substantially cylindrical body portions 13 and longitudinally disposed web portions 14. The web portions 14 are provided at the end portions of the blocks with openings 15 which receive the sleeves 10 of the plate structures. The ends of the web portions 14 are rounded as at 16 to provide 105 a space for the reception of the teeth of the wheel 4 when the blocks are passing around 110

the wheel and in order that the inner edges of the web portions 14 may bear directly against the peripheries of the bosses 5 of the wheel 4 as best indicated in Figure 1 of the drawing. The body portions of the blocks are provided with openings 17 adapted to receive picks 18 of usual form. Set screws 19 pass through the side portions of the bodies of the blocks and are adapted 10 to engage the sides of the picks 18 whereby they are securely held in position in the openings 17. The openings 17 at the opposite end portions of the blocks pass each other at acute angles so that the picks are 15 disposed at angles with relation to each other and extend at equal distances beyond the median longitudinal line of the blocks. Therefore the blocks and the picks are balanced and the picks on the several blocks 20 are spaced at different distances from each other so that when the apparatus is in use a kerf is made in the material and the opposite side surfaces of the kerf will be sufficiently smooth and the kerf will be sufficiently 25 broad to provide ample clearance space for the cutting apparatus to enter the material to the extent of the full length of the arm 1. The inner edges of the blocks 12 bear directly upon the outer surfaces of the heads 30 of the guide rails 2 and consequently the blocks are firmly supported upon the guide rails and the strap plates are firmly supported upon the edges of the arm 1. The 35 curved surfaces of the recesses 16 are substantially concentric with relation to the adjacent openings 15 and consequently the teeth of the sprocket wheel may be received in the said recesses without binding or clamping and at the same time the inner 40 surfaces of the blocks will bear directly upon the peripheries of the bosses of the wheel and consequently the picks are firmly supported during their movement along the 45 arm of the cutting apparatus and along the guide rails and also while they are passing around the peripheral portion of the sprocket wheel.

From the foregoing description of the construction and operation of my improved 50 device, it will be seen that I have provided a simple, inexpensive and efficient means

for carrying out the objects of the invention. While I have particularly described the elements best adapted to perform the functions set forth, it is obvious that various changes in form, proportion and in the minor details of construction may be resorted to, without departing from the spirit or sacrificing any of the principles of the 55 invention.

Having described the invention what is claimed is:—

1. In a cutting apparatus including a chain structure strap plates forming links in the chain structure and arranged in pairs, each member of each pair having inwardly disposed flanges, rivets connecting the members of the pairs together, spacing sleeves located upon the rivets, and pick carrying blocks having openings receiving 70 the spacing sleeves.

2. In a cutting apparatus an arm, T-shaped guide rails having their web portion inserted in the side edges of the arm and having their head portions spaced from the side edges of the arm thereby providing channels at the opposite side of the arm and a chain including strap plates having flanges slidably received in said channels and pick carrying blocks pivoted to the 75 strap plates and bearing against the outer surfaces of the head portions of the guide rails.

3. In a cutting apparatus an arm, T-shaped guide plates having their web portion inserted in the side edges of the arm and having head portions spaced from the edges of the arm thereby forming channels at the opposite side of the arm, a wheel journaled at the end of the arm and provided at its side with outstanding bosses, the inner surfaces of the channels being tangentially disposed with relation to the peripheries of the bosses and a chain including strap plates having flanges which are slidably received in the channels and adapted to engage the peripheries of the 90 bosses of the wheel.

In testimony whereof I affix my signature.

JAMES CAMERON.
